UNITED STATES PATENT OFFICE.

JOHN F. JOHNSON, OF ELMHURST, NEW YORK.

MOLDING OR TRIMMING FOR BUILDINGS.

1,065,810.

Specification of Letters Patent. Patented June 24, 1913.

Application filed February 18, 1913. Serial No. 749,083.

To all whom it may concern:

Be it known that I, JOHN F. JOHNSON, a citizen of the United States, and residing at Elmhurst, in the county of Queens and State 5 of New York, have invented certain new and useful Improvements in Moldings or Trim- mings for Buildings, of which the following is a specification, such as will enable those skilled in the art to which it appertains to 10 make and use the same.

This invention relates to moldings or trimmings for finishing the interior of buildings and particularly to moldings or trimmings composed of sheet metal, and the 15 invention consists of improved means for connecting two or more parts to form a complete molding or trimming and which may also be used in securing the said molding or trimming to a wall or other support.

20 The invention is fully disclosed in the following specification of which the accompanying drawing forms a part, in which the separate parts of my invention are designated by suitable reference characters in 25 each of the views, and in which:—

Figure 1 is a sectional view showing a sheet metal molding consisting of two parts connected according to my invention, the connection also serving as means for securing 30 the molding to a wall;—Fig. 2 a view similar to Fig. 1, but showing a molding consisting of three parts and my improved means for connecting said parts;—Fig. 3 a view similar to Figs. 1 and 2, but showing 35 another modification, and Fig. 4 a side and end view of the means which I employ in connecting two parts to form a complete molding or finishing strip.

In Fig. 1 of the accompanying drawing I 40 have shown at *a* the wall of a building and at *b* a molding comprising two parts *b*² placed together, and the adjacent side edges of which are provided with inwardly di- rected flange strips *b*³, and in connecting the 45 parts *b*² of the molding *b* I provide a plate *c* preferably approximately rectangular in form and which may be approximately square, or oblong in form, and in one edge portion of which is formed a slot *c*² having 50 diverging branches *c*³ forming a central wedge *c*⁴. In the use of this connecting de- vice *c*, in the form of construction shown in Fig. 1 where two parts are connected to form a molding, said connecting device is 55 driven onto the flange strips *b*³, or said

flange strips are driven into the slot *c*² and one of said flange strips enters one of the diverging branch slots *c*³ and the other of said flange strips enters the other of said diverging branch slots, and said flange strips 60 and the separate parts of the molding are securely locked together. The securing or locking device *c* may be countersunk in the wall *a*, if desired, or the complete molding may be secured to the wall by nails or other 65 devices passed through the outer edge por- tions thereof in the usual manner, or both of said means may be employed for securing the molding to a wall or other support.

In Fig. 2 I have shown the plate *c* pro- 70 vided with the main slot *c*² and with the branch slots *c*³, and a supplemental slot *c*⁵ forming two wedge members *c*⁶, and the molding *d* consists of four parts *d*², *d*³, *d*⁴ and *d*⁵, and the part *d*⁴ is secured to the part 75 *d*³ or a member thereof and said parts are provided with two flange strips *d*⁶ and a central flange strip *d*⁷, and said flange strips are driven into the plate *c*, or said plate is driven onto said flange strips and the wedge 80 members *c*⁶ pass between the flange strips *d*⁶ and *d*⁷, as shown in said figure, and the parts of the molding are securely locked together.

In Fig. 3 I have also shown another modi- 85 fication in which two of the locking or se- curing plates *c* are employed and one of these plates has two of the slots *c*³, as shown in Figs. 1 and 4, and the other has three of said slots the same as in Fig. 2, and two 90 wedge members *c*⁶, and the molding *e* con- sists of two main parts *e*² and *e*³ connected in L form and having flange strips *e*⁴, and the part *e*³ is composed of two separate parts having flange strips *e*⁵, and secured to 95 the outer face of the part *e*³ is a sup- plemental molding strip *f* composed of two parts one of which is provided with a flange strip *f*², and the method of connecting the 100 securing or locking plates *c* with the mold- ing *e* is clearly shown in Fig. 3 and is the same as with the construction shown in Fig. 2.

The securing or locking plate or plates *c* may be of any preferred dimensions and any desired form, and they may also aid in 105 securing the moldings or finishing strips to a wall, as shown in Fig. 1, or the molding or finishing strips may be secured to the wall in any desired manner.

Having fully described my invention what 110

I claim as new and desire to secure by Letters Patent is:—

1. A molding or finishing strip composed of separate parts and the adjacent edges of which are provided with inwardly directed flange strips, and a locking plate having a slot adapted to receive said flange strips and provided with diverging slots forming an intervening wedge.
- 10 2. A molding or finishing strip composed of separate parts provided with parallel flange strips, and a locking plate provided with a slot adapted to receive said flange strips, said slot being provided with diverging slots separated by a wedge member.

3. A molding consisting of separate parts having parallel flange strips and a locking plate provided with diverging slots adapted to receive said flange strips, and intervening wedge members adapted to separate said flange strips when the locking plate is driven thereonto.

In testimony that I claim the foregoing as my invention I have signed my name in presence of the subscribing witnesses this 25 15th day of February 1913.

JOHN F. JOHNSON.
